The ornamental design for an automobile tire, as shown and described.

DESCRIPTION

FIG. 1 is a front view showing our new design;

FIG. 2 is a right-side view thereof;

FIG. 3 is a top view thereof;

FIG. 4 is a perspective view thereof;

FIG. 5 is an enlarged cross-section view taken along the line A1—A1 of FIG. 1, in the part C—C of FIG. 2; and,

FIG. 6 is an enlarged view of the part B1-B2 in FIG. 1.

In the drawings, the broken lines defining the sidewall, inner bead and the peripheral boundary between the claimed tire tread and the unclaimed sidewall depict environmental subject matter that forms no part of the claimed design.
